UNITED STATES PATENT OFFICE.

WILLIAM F. WAYNE, OF EDWARDSVILLE, ILLINOIS.

RAIL JOINT.

Application filed March 16, 1927. Serial No. 175,750.

This invention relates to an improved rail joint which is of a construction to obviate the necessity of employing fish-plates, bolts, and similar fastening devices.

My principal object is to produce a novel joint which is believed to be an improvement upon known structures of a similar class, the improvement being characterized by simplicity in design, dependability, and strength, the arrangement being such as to allow relative freedom of movement to compensate for contraction and expansion.

Briefly, the invention comprises rail sections equipped with complementary male and female parts constructed for snug interfitting relation, and to provide a compact and rigid joint which cannot open or spread to either side.

The male member is important in that it embodies a relatively high and wide base portion carrying an upstanding tongue, whereby to provide supporting ledges on opposite sides of the tongue for the furcations of the complementary female member.

The female member is particularly advantageous in that one of the furcations operates to form a part of the wheel tread, the other being offset in an outward direction and having a lower web extension engaging the outer longitudinal edge of the base portion of the male member.

Other features of the construction will become apparent from the following description and drawings.

In the drawings:—

Figure 1 is a fragmentary top plan view showing the members in connection.

Fig. 2 is a cross section through the same.

Fig. 3 is an end elevation of the female

member of the joint.

Fig. 4 is a perspective view of the male member of the joint, and

Fig. 5 is an elevated perspective observing the under side of the female member of the joint.

Referring now to the drawings in detail, it will be seen that the reference character 1 designates one rail section, the reference character 2, the other rail section. These include the customary wheel treads 3, base flanges 4, and connecting web 5.

The rail section 2 (see Fig. 4), carries the male member of the joint, generally designated by the reference character 6, one of the primary parts of this member being the extension forming the base 7. This base

has its inner longitudinal side in alignment with the web 5 of the rail and has its other edge offset with respect to this web.

It will be noticed that this makes the base comparatively wide, and it is of a height equal to about one-half of the complete height of the rail section. Rising from the central portion of this base is an interlocking tongue 8, the upper surface of which terminates on a plane slightly below the surface of the tread 3. For convenience of description, the portions 9 and 10 on opposite sides of this tongue are to be designated as supporting ledges. At the junction of the base 7 and the main rail section is a reinforcing enlargement 11, one face of which operates as an abutment, as indicated at 12.

Referring now to Fig. 5 wherein the construction of the female member 13 is shown, it will be noticed that this comprises a bifurcated extension including furcations 14 and 15 based upon and to provide an intervening slot for accommodating tongue 8. These furcations are of a height equal to the height of the tongue 8. It will be noticed, however, that the furcation 14 is of special cross sectional configuration so as to provide a continuation of the tread section of the rail 1. The end thereof abuts the complementary tread sections of the rail 2 to provide an unbroken wheel tread. The furcation 15 is provided with a depending web 16 terminating in an outstanding flange 17. The web is of a thickness to provide a shoulder 18 on the inner side to engage the ledge 10. This arrangement also provides an abutment surface 19 with which the end of the base 7 cooperates.

It is plain that with this construction, when the two members of the joint are in interlocking connection, the furcations 14 and 15 rest upon the ledges 9 and 10 while the tongue 8 extends into the slot between the furcations. The end of the furcation 15 engages the abutment 12, and the end of the base 7 engages the abutment surface 19.

The web 16 contacts the outer longitudinal face of the base 7. It will thus be seen that the tongue and slot connection comes on the outside of the rail and at a point beyond the wheel treads 3. It will also be noticed that the upper surfaces of the reinforcement 11, furcation 15, and tongue 8, are in a plane with each other but on a plane below the tops of the wheel treads.

The particular construction, as well as the advantages derived therefrom will undoubtedly be clear to persons familiar with rail joint structures. For this reason, a more detailed description is thought unnecessary.

While the preferred embodiment of the invention has been shown and described, it is to be understood that minor changes in the size, shape and arrangement coming within the scope of the adjoined claim may be resorted to if desired.

Having thus described my invention, what I claim as new is:—

15 In a structure of the class described, a

rail section having a relatively thick and wide base extension provided with an upstanding tongue on opposite sides of which are supporting ledges, a reinforcement at the juncture of the base and body of said rail section, a complemental rail section provided with a bifurcated portion, the furcations straddling said tongue and resting on said ledges, one furcation providing a wheel tread continuation, and the other furcation being provided with a depending web engaging the outer longitudinal face of the aforesaid base.

In testimony whereof I affix my signature.

WILLIAM F. WAYNE.
